US00D943792S

(12) **United States Design Patent** (10) **Patent No.:** **US D943,792 S**
(45) **Date of Patent:** **** Feb. 15, 2022**

(54) **LIGHTING DEVICE**

(71) Applicant: **MAINHOUSE (XIAMEN) ELECTRONICS CO., LTD**, Fujian (CN)

(72) Inventors: **Nanqing Zhou**, Fujian (CN); **Jianyun Zhong**, Fujian (CN)

(73) Assignee: **MAINHOUSE (XIAMEN) ELECTRONICS CO., LTD**, Fujian (CN)

(**) Term: **15 Years**

(21) Appl. No.: **29/692,867**

(22) Filed: **May 29, 2019**

(30) **Foreign Application Priority Data**

Dec. 19, 2018 (CN) 201830737771.8

(51) **LOC (13) Cl.** **26-02**

(52) **U.S. Cl.**

(57) **CLAIM**

The ornamental design for a lighting device, as shown and described.

DESCRIPTION

FIG. 1 is a front elevational view of a lighting device showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a front perspective view thereof in use status;

FIG. 10 is an enlarged partial view of the indicated portion on FIG. 6; and,

FIG. 11 is an enlarged partial view of the indicated portion on FIG. 2.

The broken lines in the figures depict portions of the article and environmental subject matter, which form no part of the claimed design.

1 Claim, 11 Drawing Sheets
